UNITED STATES PATENT OFFICE.

FRANK A. LUCAS, OF DETROIT, MICHIGAN.

CARBURETER.

1,368,950.

Specification of Letters Patent. Patented Feb. 15, 1921.

Application filed November 8, 1918. Serial No. 261,604.

To all whom it may concern:

Be it known that I, FRANK A. LUCAS, a citizen of the United States of America, residing at Detroit, in the county of Wayne, 5 and State of Michigan, have invented certain new and useful Improvements in Carbureters, of which the following is a specification, reference being had therein to the accompanying drawings.

10 The object of my invention is to simplify the construction and cheapen the cost of carbureters, and at the same time provide a more efficient carbureting device that may be characterized in the following particulars.

15 First, the carbureter includes a stationary Venturi member and a valvular member movable relative to said Venturi member, said valvular member obviating the necessity of using the ordinary throttle or butterfly valve in the upper portion of the carbureter.

20 Second, there is an annular fuel outlet port positioned in proximity to the Venturi and valvular members so that there is a constant annular source of fuel that may be withdrawn for admixture with air, this constantly open source of fuel being in contradistinction to a valve regulated supply 25 and a supply delivered at a multiplicity of places relative to the Venturi member or the mixing chamber of the carbureter.

25 Third, the carbureter includes a novel by-path construction which permits of sufficient fuel being withdrawn from the supply for engine idling purposes when air is shut off or approximately so to the carbureter.

30 Fourth, the carbureter is characterized by a mechanical construction consisting of comparatively few parts, easy to assemble and of such a nature as to be properly proportioned for a duty predetermined in connection with any engine, thus obviating the necessity of using one make of carbureter for one type of engine. With my carbureter it is only necessary, in the initial assembling, to properly position the Venturi member 35 relative to the constantly open fuel supply 40 port.

45 The above is a brief outline of the main features of my invention, and reference will now be had to the drawing, wherein—

50 Figure 1 is a vertical longitudinal sectional view of the carbureter, and

Fig. 2 is a horizontal sectional view of a portion of the same taken on the line II—II of Fig. 1.

55 In describing my invention by aid of the views above referred to it is to be understood that the structural elements are illustrated merely as an example of the preferred form of the carbureter, and that the construction entering into the same is susceptible to such modifications and variations as are necessary to render the carbureter efficient for a particular duty.

60 In the drawing, the reference numeral 1 denotes an air intake elbow connection which has the lower or outer end thereof 65 provided with a conventional form of butterfly valve or air throttle 2. Preferably formed integral with one side of this air intake connection, at the upper end thereof, is a float chamber 3 provided with a detachable cap 4 supporting a conventional form of needle valve 5. The float chamber 3 is in communication with a fuel supply pipe 6 and within the float chamber is an ordinary float 7 for automatically actuating a valve 8 which controls the supply 70 of fuel to the float chamber 3 and regulates the supply so that a constant level of fuel is maintained within the float chamber.

75 The upper end of the air intake connection 1 is provided with an annular stepped recess 9 and the inner end of said recess affords an annular shoulder or seat 10 for the inner end of a cylindrical shell or wall member 11 that cooperates with the annular 80 wall of the recess 9 in providing an annular fuel holding channel or port 12 which is constantly open and receives fuel from the float chamber 3 through the medium of ports 85 13 and 14. The port 13 has its upper end 90 opening into the channel 12 and its lower end communicating with the port 14, said port being in the lower part of the float chamber 3 to receive fuel when the needle valve 5 is properly adjusted. The float 95 chamber, together with its communicating ports, constitutes a source of fuel supply for the carbureter and means for maintaining a constant level of fuel within the channel 12.

100 Mounted on top of the air intake connection 1 is a casing providing mixing chamber 15 having a depending end portion 16 extending into the recess 9 of the air intake connection 1 and restricting the chan-

105

110

nel 12 relative to the wall member 11, so as to provide a narrow annular port at the upper edge of the wall member 11, said port having for its inner wall the sleeve or wall member 11 and for its outer wall an end portion 16 of the mixing chamber 15, particularly at the juncture of the end portion 16 and the mixing chamber 15. As clearly shown in Fig. 1 the greater portion of said port is vertical and its upper end terminates in a small lateral portion circumferentially of the upper edge of the sleeve or wall member 11.

Fixed in the mixing chamber 15 is a Venturi member 17 providing an annular seat 18 in proximity to the lower end of the mixing chamber. This Venturi member is ported, as at 19, to receive communicating by-path tubes 20 and 21, the former extending into the upper portion of the Venturi member 17, above the seat 18, and the latter depending from the seat 18 into the end portion 16 of the mixing chamber. The lower end of the by-path tube 21 is bent so as to confront the outer wall of the annular fuel port, designated 22, so that fuel may be withdrawn from said port and discharged into the upper portion of the Venturi member 17.

Suitably mounted in the air intake connection 1 is a post 23 that is concentric of the sleeve or wall member 11 and in the axis of the mixing chamber 15. The post may have its lower end conveniently attached to the air intake connection 1, as at 24, and its upper end is adapted to extend into the upper portion of the Venturi member 17. Slidable on said post is the sleeve or tubular guide member 25 of a throttle or valvular member 26, which is preferably hollow. The valvular member 26 for the greater part of its length is cylindrical so as to coöperate with the sleeve or wall member 11 in providing an annular passage leading past the annular port 22 into the lower end of the Venturi member 17, and the upper end of said valvular member is conical or tapered so as to concentrically engage the seat 18 and shut off the main supply of fuel through the Venturi member 17, without interfering with the auxiliary supply through the by-path tubes 20 and 21 for engine idling purposes.

Extending into the lower end of the air intake connection 1 and through suitable bearings 27 provided therefor, is a rock shaft 28 having inner and outer crank portions 29 and 30, the latter permitting of the shaft 28 being rocked or adjusted. The inner crank portion 29 is loosely connected to a head 31 on the lower end of the sleeve or tubular guide 25 of the valvular member 26, the elements 27 and 31 inclusive constituting means operable at the air intake connection 1 and below the valvular member

26 for adjusting said valvular member relative to the stationary Venturi member 17 of the carbureter.

As briefly referred to in the beginning the annular constantly open fuel port 22 is in contradistinction to a plurality of independent fuel supply ports and by having this fuel port constantly open and communicating with an annular air passage, it is obvious that velocity of air through the passage produced by an engine or any starting device will cause the air to be more or less saturated with fuel and as the vapor passes upwardly it impinges against the seat 18 of the Venturi member 17 and is directed toward a vortex in the upper portion of the Venturi member which constitutes a mixing chamber and insures a thorough commingling of fuel and air due to the seat 18 of the Venturi member 17 and the upper end of the valvular member 26 directing the fuel to the axis of the mixing chamber 15. This is particularly true when the valvular member 26 is wide open with the engine producing a high velocity of air past the open port 22, whereas with the valvular member 26 slightly off of the seat 18 the fuel has a chance to spread in the upper portion of the Venturi member and thus prevent stratification of air and fuel in the mixing chamber.

The constantly open fuel port 22 has the advantage over a plurality of orifices in presenting a large surface of gasolene or other fuel to the air, so as to be attacked thereby, besides being easier and cheaper to produce than small drilled or otherwise formed orifices.

I attach considerable importance to the fact that the Venturi member 17 is stationary and fixed in the mixing chamber 15 so as to have a defined position relative to the end portion 16 of the mixing chamber, such position being determined and made non-adjustable according to the duty to be performed by the carbureter. This is also true in connection with the sleeve or wall member 11 which may be of a height to coöperate with the mixing chamber in providing the fuel port 22 with an opening of sufficient area so as not to retard the withdrawal of fuel from the channel 12. In other words, one make of engine may require a fuel port of more or less area than another make of engine and after such is determined, the sleeve or wall member is provided which will insure a proper degree of opening at the constant supply of fuel in the upper end of the air intake connection. The Venturi member 17, being stationary, permits of the member 26 acting as a valve movable to and from the member 17, and in actual practice, the stationary member 17 saves material and obviates connections that would be necessary if it were movable relative to

the valve member. It is now apparent that the carbureter consists of very few adjustable parts, which is a desideratum especially in connection with carbureters for 5 air crafts. After my carbureter is once installed and properly adjusted there is only one adjustment, that of the valvular member 26 and this materially simplifies an intelligent operation of a motor by vehicle or air 10 craft, as far as fuel supply is concerned. Again, use of a fuel port of the particular type herein employed standardization of parts may be attained and, as pointed out before, the only possible differentiation may be in 15 the position of the Venturi member 17 with reference to the annular fuel port 22 and in connection with the sleeve or wall member 11, which may be made of various depths with each depth to coöperate with the carbureter in producing a known result with a 20 known type of engine. I am aware that a great many carbureters have been invented having shiftable Venturi members, valved fuel ports, throttles and other adjustable elements, all necessitating specializing, expensive manufacture and considerable experience before desired results are attained. Broadly, I aim to eliminate complication 25 and expense of manufacture by my improved carbureter. 30

What I claim is:—

A carbureter comprising an air intake connection, a casing thereon providing a mixing chamber, a fixed Venturi member in said casing providing a valve seat, a cylindrical shell carried by said air intake connection and extending into the lower end of the mixing chamber of said casing and coöoperating with said air intake connection and the lower end of said casing in providing a constantly open fuel port, means adapted to supply fuel to said port, and a cylindrical valve having a conical end movable to and from the valve seat of said Venturi member and constantly presenting a wall toward the fuel port to coöperate with said cylindrical shell in providing a passage leading past said fuel port, said valve controlling the outlet of the mixture from the carbureter. 45

In testimony whereof I affix my signature 50 in the presence of two witnesses.

FRANK A. LUCAS.
